UNITED STATES PATENT OFFICE.

SAMUEL F. STEIN, OF WILLIAMSPORT, PENNSYLVANIA.

MOTION-PICTURE APPARATUS.

1,307,323.

Specification of Letters Patent. Patented June 17, 1919.

Application filed July 17, 1918. Serial No. 245,283.

To all whom it may concern:

Be it known that I, SAMUEL F. STEIN, of Williamsport, in the county of Lycoming and State of Pennsylvania, have invented a 5 certain new and useful Improvement in Motion-Picture Apparatus, and do hereby declare that the following is a full, clear, and exact description thereof.

My invention relates to so-called speaking 10 motion pictures, that is, to the joint use of motion pictures and talking machines, so that when talking or singing characters are projected on the screen, the appropriate words or sounds will simultaneously be 15 given by the phonograph, and generally stated, my object is to secure a uniform or equitable distribution of the sound to all parties of the auditorium and diminish the likelihood of want of coördination or syn- 20 chronizing of pictures and sounds. To this end, and to secure other advantages, my invention consists in the construction or correlation of parts substantially as hereinafter specified.

25 In the drawings.

Figure 1 is a view diagrammatic in nature, of one embodiment of my invention, showing the same viewed from above.

Fig. 2 is a detail back view of one of the 30 chairs and adjacent parts.

Briefly described, my invention comprehends the employment of a talking-machine or phonograph in connection with a record appropriate to the moving picture, which 35 acts upon a telephone transmitter from which radiate to all parts of the auditorium circuit wires, or conductors with their terminals at or near the seats therein, and provided either permanently or detachably, with telephone 40 receivers for the use of the seat occupants. Thus, each auditor will have directly transmitted to him, and with the same force, or volume of sound, the talk or other utterances, or sounds rendered by the talking 45 machine, and the serious objection is overcome to the use of a phonograph in that if its sound is loud enough to reach to the auditors in the rear of the theater, it is objectionably loud to those at front, and if it 50 is moderated so as to be unobjectionable to those in the front, it is too low to be heard elsewhere. Again, more perfect synchronism of pictures and sounds is obtainable, first, because projector machine and phonograph can be close connected for operation 55 (since by my invention the phonograph need

not be close to the screen, as it makes no difference where it is located) and second, because the sounds being electrically transmitted, they reach the auditor simultaneously with the sight of the pictures, the difference between the rates of travel of light and sound not being a factor in the case.

In the drawings, 10 designates a motion 65 picture screen; 11 a projector machine; 12 a phonograph, operatively connected with the projector machine so they run in unison; 13 a telephone transmitter that has a dia- 70 phragm that is actuated in correspondence with the vibrations of the diaphragm of the phonograph, either directly by mechanical connection or through the air, or is itself provided with a stylus and directly operated 75 by the record; 14, the line of wires running from the transmitter to all parts of the auditorium, so that simultaneously the sounds from the same record are sent to all the seats 15 of the auditorium; and 16, the receivers at the seat terminals of said line 80 wires. The receivers may be permanently secured to such terminals, but they are preferably detachably connected to enable persons to own their own receivers, just as they do opera glasses, or to enable them to be 85 hired at the box office or theater. The place of connection is such as not to interfere with free passage of the persons between the rows of seats, and, preferably, the place of connection is at the side or back of the chair 90 occupied by the user, as thereby the conductor wires leading to the receiver will be wholly out of the way. Thus, as shown in Fig. 2 the terminal 17 (which may be a plug 95 socket) is secured to the chair back 18, near the top thereof, and the wires leading thereto are carried through a vertical tube 19 alongside the chair, branching from the main tube or conduit 20.

The receiver 16 may have a spring clamp 100 16^a to hold the instrument to user's head, and said clamp may be detachable, so that all the user will be obliged to carry, will be such clamp and not the whole receiver which latter may thus be always left at the chair. 105 The clamp may be rendered sanitarily safe by any of the usual expedients for this purpose, if it or the receiver to which it is attached is promiscuously used by the public and not owned by the individual. To this 110 same end I provide the clamp with a thin member 22 that prevents contact of the ear

or head of the user, with the transmitter body 21.

If, in consequence of wear, portions of film should be cut out, that would result in 5. getting record and film out of synchronism, should the ends between the cut out portion be joined, I avoid that result by putting an insert of blank film in place of the cut out

- 10 I distribute the blank portion in sections alternating with retained portions of the picture, so that an unobjectionable series of short interruptions to the continuity of the picture would result instead of a long ob-
15 jectionable one.

To prevent the noise of the projector machine reaching the telephone transmitter when the latter is quite close to the projector machine to enable the direct and close driving of the phonograph from the projector machine shaft, I interpose a partition 23 of some usual deadening material.

The parallel connection of the receivers in, 25 the circuit renders practicable the detach- ability of the receivers, in that the removal or absence of one or more receivers would not interfere with the operation of those that remain.

By providing, as my invention does, for 30 the transmission of the words or other sounds to the individual spectators, and not to the audience generally, it is possible that both

classes of patrons, those who want to hear as well as see, and those who want to see and not hear, are provided for, because no one 35 who cares not to hear need use the receiver and unless he does use it, he will not hear the production of the phonograph.

I claim:

1. The combination of a picture project- 40 ing machine, a phonograph for producing sounds pertinent to the pictures projected by the projecting machine, a plurality of telephone receivers, seats with which the receivers are respectively associated for the individual use of seat occupants, and means for transmitting sounds from the phonograph to the receivers comprising a circuit acted upon by the phonograph with which circuit the telephone receivers are connected in par- 45 allel, the receivers being detachable.

2. The combination of a picture projecting machine, seats for spectators, a phonograph for producing sounds pertinent to the pic- 50 ture projected by the projecting machine, a telephone transmitter actuated by the phonograph, a plurality of circuits in parallel leading from said transmitter to the respective seats, and a telephone receiver for each circuit having a detachable connection there- 55 with.

In testimony that I claim the foregoing I have hereunto set my hand.

SAMUEL F. STEIN.
